UNITED STATES PATENT OFFICE.

GEORGE B. CLOUGH, OF MERIDEN, CONNECTICUT.

PRICE INDICATOR.

Application filed February 23, 1922. Serial No. 538,446.

To all whom it may concern:

Be it known that I, GEORGE B. CLOUGH, a citizen of the United States, and a resident of Meriden, county of New Haven, and State 5 of Connecticut, have invented certain new and useful Improvements in Price Indicators, of which the following is a specification.

This invention relates to improvements in 10 price indicators, and more especially to indicating means for designating the price of gasoline.

An object of the invention is to provide a suitable indicating device for use at automobile or gasoline service stations to clearly 15 show the price of gasoline per gallon.

Another object of the invention is to provide a price indicating device for gasoline stations, which will be so constructed, that 20 any combination of digits may be quickly formed, to show the price of gasoline or oil at the time the purchase is made.

A further object of the invention is to provide a suitable price indicating device 25 for gasoline service stations which will be simple, cheap to manufacture, and highly efficient and durable in use.

With these and other objects in view, there 30 has been illustrated in the accompanying drawings one form in which the invention may be conveniently embodied in practice.

In the accompanying drawings which constitute a part of the application,

Fig. 1 is a perspective view of the price 35 indicating device, showing the several parts in knocked-down position.

Fig. 2 is a perspective view taken from the rear of the indicating device, showing it in closed or assembled position.

Fig. 3 is a perspective view of the attaching means for the same.

Fig. 4 is a front elevation of the device.

Like characters of reference are used throughout the several views to designate 45 corresponding parts.

A casing or housing 1 of the indicating device is made preferably rectangular in shape, and has its front face open. Integrally formed at the bottom edge of the casing 1, are depending clips or hinges 2, which 50 cooperate with like members 3, on a cover 4, the same being held in operative position by means of a pivot pin 5.

The cover 4 is of the same general shape 55 as the casing 1, and is provided with rec-

tangular openings 6 and 7. These openings 6 and 7 are covered by glass plates 8, and the opening 7 extends below the openings 6 and is provided at its upper and lower edges with angular flanges 9. A card 10 is adapted to slide into the flanges 9 and has printed thereon "Per gallon including tax". It is intended that the card 10 will be left in place within the flanges 9, so that the inscription thereon may be readily seen 65 through the front of the opening 7.

A frame or holder 11 is hingedly supported on a rod 12, which rod is pivoted between the side walls of the casing 1 and is provided with coil springs 13 for normally 70 pressing said frame 11 against the back wall of the casing 1. The frame 11 is preferably formed from a single piece of sheet metal, and has its sides and bottom bent over to form angular flanges 14 and 15. Adjacent 75 the central portions of said frame, and stamped upwardly therefrom are oppositely extending angular ears 16, 16^a.

In order to indicate the price of the gasoline to actual or prospective purchasers, 80 two packs or sets of digit cards 17 are provided. These packs of digit cards are detachably held in place in the two parts of the frame or holder 11 by means of the flanges 14, 15, and ears 16, 16^a, so that the digit on the front card of each pack will be visible through the front openings 6 of the cover 4. Each pack is provided with cards 85 whose digits run from 0 to 9 and each card has an index tab on its upper edge which 90 corresponds with the large digits printed thereon.

A grooved or dove-tailed socket member 18 is attached to the back of the casing 1 in any suitable manner, as by bolts 18^a. This 95 socket member 18 is adapted to receive a wedge portion 19 which may be secured to a post or positioned in any other suitable place near a gasoline filling station.

In order to detachably lock the cover 4 to the casing 1, a threaded bolt 20 is pivotally connected to a block in a U-clip 21 on the cover. A thumb nut 22 threaded on the bolt 20 serves to hold the cover firmly to the casing.

To permit the device to be readily opened for rearranging the digits in the packs, a knob 23 of any suitable design is placed on the front of the cover 4.

In operation, assuming that the indicating 110

device is in closed position, when it is desired to change the reading of the price of gasoline, it will only be necessary to unscrew the thumb nut 22, and open the cover 4 by 5 grasping the knob 23. The frame or card holder 11 may then be swung out against the tension of the springs 13 to the position shown in Fig. 1, and the desired cards placed at the front of each pack, thereby correcting 10 the reading. As soon as the holder is released, it will snap back under the influence of the springs 13 into position against the rear wall of the casing. The cover 4 may then be closed and locked.

15 It will be understood that this device may be made in any desired size or shape, and that it may be used for advertising any desired materials including alcohol, oils, etc., but it is preferably used in connection with 20 the selling of gasoline.

Many minor changes in details of construction may be resorted to without departure from the spirit of the invention.

While there has been disclosed in this 25 specification one form in which the invention may be embodied, it is to be understood that this form is shown for the purpose of illustration only, and that the invention is not to be limited to the specific disclosure but may 30 be modified and embodied in various other forms without departing from its spirit. In short, the invention includes all the modifications and embodiments coming within the scope of the following claims.

35 Having thus fully described the invention, what is claimed as new, and for which it is desired to secure Letters Patent, is:

1. An indicator comprising a casing, a 40 perforated cover hinged to said casing, a card holder hinged within said casing, tensioning means for said card holder operating to force said card holder against said casing, and a plurality of digit cards within said holder.

45 2. An indicator comprising a casing, a cover hinged to said casing, said cover having a perforation, a card holder hinged within said casing, said holder having a plurality of intermediate oppositely directed upstanding flanges a pack of digit cards carried by 50 said holder and positively held within said flanges, so that the face of said pack will register with the perforation in the cover,

whereby any desired number will be displayed.

3. An indicator comprising a casing, a cover hinged thereto, said casing having a plurality of openings in the front thereof, flanges adjacent one of said openings, a card 60 slideable in said flanges, a card holder pivoted within said casing, digit cards carried by said holder, said digit cards registering with the other of said openings in said cover, whereby any desired number may be displayed through the cover.

4. An indicator comprising a casing, a card holder hinged therein, a spring operating to force said card holder against said casing, a cover hinged to said casing, said cover having an opening, a plurality of 70 packs of digit cards carried by said holder adapted to register with and show through the opening of the cover, and means carried by the casing and cover for locking the same in closed position.

5. A price indicator comprising a casing, a card holder hinged therein, a cover hinged to said casing, a plurality of packs of digit cards carried by said holder, tensioning means for forcing the holder against said 80 casing, means for locking the casing and cover together, and attaching means carried by the casing whereby said indicator may be secured to any desired object.

6. A price indicator for gasoline stations, 85 comprising a box having a casing, a cover pivoted to said casing, and means for carrying a plurality of packs of index cards pivoted within said box and visible through said cover for displaying digits representing the price, said means having a spring connected therewith for forcing said means against said casing.

7. A price indicator for gasoline, alcohol, oil and the like comprising a water-proof receptacle, one side of said receptacle having a transparent portion, and means for carrying two packs of index cards pivoted within said receptacle for displaying digits, said digits being visible through the transparent 100 portion of the receptacle, said means being spring-pressed to hold it against said casing.

In testimony whereof, I have affixed my signature to this specification.

GEORGE B. CLOUGH.
